UNITED STATES PATENT OFFICE.

HERMAN GETZ, OF ST. LOUIS, MISSOURI.

DESIGN FOR A BADGE.

SPECIFICATION forming part of Design No. 37,020, dated July 5, 1904.

Application filed June 10, 1904. Serial No. 212,049. Term of patent 3½ years.

To all whom it may concern:

Be it known that I, HERMAN GETZ, a citizen of the United States, residing at St. Louis, Missouri, have invented a new, original, and ornamental Design for Badges, of which the following is a specification, reference being had to the accompanying drawing, forming a part thereof.

The figure is a plan view of a badge, showing my new design.

What I claim as new, and desire to secure by Letters Patent, is—

The ornamental design for a badge, as shown.

HERMAN GETZ.
